UNITED STATES PATENT OFFICE.

JAMES HOLLEY, OF WEST PALM BEACH, FLORIDA, ASSIGNOR OF ONE-HALF
TO MARION E. GRUBER, OF WEST PALM BEACH, FLORIDA.

BRACE.

SPECIFICATION forming part of Letters Patent No. 745,059, dated November 24, 1903.

Application filed March 27, 1903. Serial No. 149,814. (No model.)

To all whom it may concern:

Be it known that I, JAMES HOLLEY, a citizen of the United States, and a resident of West Palm Beach, in the county of Dade and State of Florida, have invented a new and Improved Brace, of which the following is a full, clear, and exact description.

This invention relates to a brace provided with a plurality of tools permanently attached thereto, said tools being mounted in a movable holder, so that any one of the tools may be moved into position for operation the same as a tool or bit applied to an ordinary brace.

The invention involves, in addition, various minor features of structure and arrangement, all of which will be fully described hereinafter.

This specification is an exact description of one example of my invention, while the claims 20 define the actual scope thereof.

Reference is to be had to the accompanying drawings, forming a part of this specification, in which similar characters of reference indicate corresponding parts in all the views.

25 Figure 1 is a sectional view of the invention. Fig. 2 is an elevation looking in the direction of the arrow *a* in Fig. 1 and showing the head of the brace with the carrier and tools removed, and Fig. 3 is an elevation looking in the direction of the arrow *b* in Fig. 1 and showing the inner end of the carrier.

10 indicates the shoulder or breast knob of the brace, 11 the crank, which is provided with a handle 12, as usual, and 14 indicates 35 the head of the brace, which is carried rigidly at the side of the crank opposite the shoulder-knob 10. The head is formed with a flaring opening 15, from the outer or lower side of which extends a radial opening 16. In the 40 opening 15 is mounted to rotate the carrier 17, which conforms to the shape of the opening and is provided with a number of grooves 18, disposed longitudinally of the carrier. These grooves are adapted to receive the

45 shanks 19 of the various tools 20, said shanks having slots 19^a therein, by which they are engaged with and thus mounted to swing on a pivot-ring 21. This ring is placed in a circular recess 22 in the inner end of the carrier, such recess being best shown in Fig. 3. The slots 19^a enable the tools to be placed in

and taken from the brace. The walls of the cavity or opening 15 keep the tools 20 in folded position—that is to say, extending longitudinally of the axis of the turning movement of the carrier 17. When, however, one of the tools reaches a position opposite the radial slot 15, said tool may be swung outward into the position shown in the top of Fig. 1, and the tool lying in this slot will then 55 be held rigidly. For preventing the tool from returning to its folded position I provide a catch 21^a, which is in the form of a lever fulcrumed at the point 22^a and having at one end a finger-piece 23. A spring 24 presses 60 the upper end of the lever outward from the head 14, thus throwing the bill 25 into a notch 26, formed in the shank of the tool. The inner walls of this notch are curved in the arc of the movement of the bill 25 of the catch 65 21^a, and said bill is correspondingly hooked, and therefore when the catch is in active position the tool 20 cannot be moved down into folded position. By throwing the bill 25 out of said notch the tool is then free to move. 70 The catch 21^a is placed in a transversely-extending cavity 27, formed in the outer side of the head 14 of the tool.

The carrier 17 is mounted to turn around a shaft 28, one end of which is seated in the 80 head 14, said carrier bearing between this head and a collar 29 on the shaft 28. A guard 30 is arranged to cover the points of the tools 20, said guard turning on the shaft 28 and on an extension 31 of a brace-arm 32, 85 said extension having a collar 33 thereon and the shaft 28 having a second collar 34, between which collars the hub of the guard 30 bears. The guard is formed with a peripheral notch 35, which receives the arm 32 and 90 prevents rotation of the guard. Said guard is, however, capable of being moved outward to permit the passage of the tools 20 past it, and a spring 36 is provided to hold the guard 95 yieldingly in active position.

In the use of the invention the carrier 17 should be revolved around the spindle or shaft 28, so as to place the desired tool opposite the groove or slot 16. This tool should then be moved out into active position and 100 the catch 21^a engaged therewith. The brace may now be operated in the usual manner.

Should it be desired to use a different sort of tool, the first-mentioned tool may be thrown down into folded position and the next desired tool moved outward. In order to thus adjust the device, it is necessary to shift the guard 30, and this is effected by manually moving said guard out from the tool. Tools of any sort may be fitted to the brace. It is especially adapted for boring instruments, although, of course, other tools may be employed—such, for example, as the one indicated at the lower side of the carrier in Fig. 1.

Various changes in the form, proportions, and minor details of my invention may be resorted to at will without departing from the spirit and scope thereof. Hence I consider myself entitled to all such variations as may lie within the intent of my claims.

Having thus described my invention, I claim as new and desire to secure by Letters Patent—

1. A brace, comprising a cranked shank, a head rigidly mounted thereon and having a radial slot, a carrier arranged to turn with respect to the head, a plurality of tools mounted on the carrier and capable of being moved independently to lie outward of the head, a shaft engaged with the head and on which shaft the carrier is mounted to turn, means for holding the outer end of the shaft in place, said means comprising an arm attached to the shaft, and a guard having a hub receiving the adjacent ends of the shaft and arm and movable axially thereon, for the purpose specified.

2. A brace, comprising a cranked shank, a head carried thereby, a shaft engaged with the head, a carrier mounted to turn on the shaft, a plurality of tools adjustably mounted on the carrier and capable of being independently moved outward into engagement with the head, an arm attached to the shank and having an extension projected into proximity with the outer end of the shaft, and a guard inclosing the adjacent ends of the arm and shaft and being axially movable thereon, for the purpose specified.

3. A brace, comprising a cranked shank, a head carried thereby, a shaft engaged with the head, a carrier mounted to turn on the shaft, a plurality of tools adjustably mounted on the carrier and capable of being independently moved outward into engagement with the head, an arm attached to the shank and having an extension projected into proximity with the outer end of the shaft, a guard inclosing the adjacent ends of the arm and shaft and being axially movable thereon, for the purpose specified, and a catch mounted on the head and capable of removably holding the tools into engagement therewith.

4. A brace, comprising a cranked shank, a head carried thereby, a shaft engaged with the head, a carrier mounted to turn on the shaft, a plurality of tools adjustably mounted on the carrier and capable of being inde-

ently moved outward into engagement with the head, an arm attached to the shank and having an extension projected into proximity to the outer end of the shaft, a guard inclosing the adjacent ends of the arm and shaft and being axially movable thereon, for the purpose specified, and a spring pressing said guard into active position.

5. A brace, comprising a head having a cavity or recess therein, a carrier having a portion projected into said cavity, means for mounting the carrier to turn in said position, the carrier being formed with a number of longitudinal slots, and a plurality of tools having their shanks pivoted in said slots, the head having a radial slot and with which any one of the slots of the carrier may register, whereby to permit the tools to be thrown outward into said slot of the head, for the purpose specified.

6. A brace, comprising a head having a cavity or recess therein, a carrier having a portion projected into said cavity, means for mounting the carrier to turn in said position, the carrier being formed with a number of longitudinal slots, a plurality of tools having their shanks pivoted in said slots, the head having a radial slot and with which any one of the slots of the carrier may register, whereby to permit the tools to be thrown outward into said slot of the head, for the purpose specified, and a catch for removably holding the tools in said slot.

7. A brace, comprising a cranked shank, a head mounted thereon, a shaft engaged with the head, a carrier mounted on the shaft, a plurality of tools mounted on the carrier and capable of independent engagement with the head, an arm attached to the shank and extending into proximity to the outer end of the shaft, and means connecting the arm and shaft, for the purpose specified.

8. The combination of a head, a tool pivoted to swing thereon and having a recess removed from the pivot, and a catch pivotally mounted on the head and having a bill coacting with the recess of the tool, for the purpose specified, the walls of said recess being curved and the bill of the catch being correspondingly hooked.

9. A brace, comprising a head having a cavity therein, a carrier, means for mounting the carrier movably with respect to the head, a plurality of tools pivoted on the carrier and capable of movement independently into said cavity in the head, and a catch pivoted on the head, each tool having a curved recess therein and the catch having a correspondingly hooked portion capable of entering into said recesses, for the purpose specified.

10. A brace, comprising a cranked shank, a head at one end of the shank, said head lying outside of the crank thereof, a carrier lying outside of the crank of the shank adjacent to the head, means for mounting the carrier in said position, and a plurality of tools adjustably mounted on the carrier and capa-

ble each of independent engagement with the head.

11. A brace, comprising a cranked shank, a head at one end of the shank, said head lying outside of the crank thereof, a carrier lying outside of the crank of the shank adjacent to the head, means for mounting the carrier in said position, a plurality of tools adjustably mounted on the carrier and capable each of independent engagement with the head, the said means for mounting the carrier comprising a shaft engaged with the head, a supporting member attached to the

shank and projecting outward into proximity to the shaft, and a guard engaged with the shaft and said supporting member and normally inclosing the points of the tools on the carrier.

In testimony whereof I have signed my name to this specification in the presence of two subscribing witnesses.

JAMES HOLLEY.
